UNITED STATES PATENT OFFICE.

MAX GÖHLER, OF ZURICH, SWITZERLAND.

CARBURETER.

SPECIFICATION forming part of Letters Patent No. 688,408, dated December 10, 1901.

Application filed January 21, 1901. Serial No. 44,196. (No model.)

To all whom it may concern:

Be it known that I, MAX GÖHLER, a citizen of the Republic of Switzerland, whose post-office address is 181 Dufourstrasse, Zurich, 5 Switzerland, have invented new and useful Improvements in Gas-Producing Apparatus, (for which I have made application for patents in Switzerland, dated November 17, 1900; in Italy, dated December 19, 1900; in Austria, 10 dated December 20, 1900; in France, dated December 21, 1900; in Belgium, dated December 21, 1900; in Hungary, dated December 21, 1900; in Denmark, dated December 21, 1900; in Germany, dated December 22, 1900; in 15 Sweden, dated December 22, 1900, and in Great Britain, dated January 1, 1901, No. 51,) of which the following is a specification.

My invention relates to an improved construction of gas-producing apparatus which 20 principally differs from others used for a like purpose, inasmuch as there is always comparatively little crude liquid, (liquid hydrocarbon or gasolene,) as well as an exceedingly small quantity of gas, present in the apparatus. The gas-generator is also completely 25 surrounded by water, which, warmed automatically, can be retained at any suitable temperature for the purpose of facilitating the gasification of crude liquids difficult to 30 evaporate, and which water-jacket practically also obviates the danger of explosions—for instance, in case of fires—as should the small quantity of crude liquid in the interior become hot it will quickly gasify and owing to 35 the increase in the pressure could escape into the atmosphere through an opening formed in the water-jacket, the latter therefore obviating a sudden large and thus dangerous inward heating. Should even extraordinary 40 circumstances cause an explosion, it would not be so disastrous as in other systems where a large quantity of crude or explosive liquid is present.

The apparatus works very economically 45 and rationally, loss of gas being entirely prevented, and all crude liquids, even such which are difficult to gasify, are uniformly converted to gas.

The apparatus is also very easy to manipulate, takes up comparatively little space, and can be installed in rooms occupied by people without danger to them, and being driven by

weight instead of motor power the working expense in this respect is *nil*.

I attain these objects by the mechanism 55 illustrated in the accompanying drawings, in which—

Figure 1 is a front view; Fig. 2, a side view; Fig. 3, a cross-section at line A B of Fig. 2; Fig. 4, a cross-section at line C D of Fig. 1, 60 and Fig. 5 a view of a detail.

Similar characters refer to similar parts throughout the several views.

In carrying out my invention I employ in the lower part of the apparatus a fan 1, which, 65 as shown in Fig. 2, is rotated by means of a weight actuating a rope-drum, draws in air at 3, and delivers it at 4. Above this fan a gas-generator 5 is employed, which is surrounded by a water-jacket 6. The said gas- 70 generator is internally formed with disks 7, which divide it in various gasifying compartments having at the bottom ports 8, allowing the crude liquid to pass from one compartment to the other. Between the said 75 disks other disks 11 are secured upon a shaft 10. The sides of these disks are faced with some porous material, such as felt, and also formed with ports and buckets 9. (See more particularly Fig. 3.) The said shaft is rotated 80 from the fan-shaft by chain-gearing 12. Above the said gas-generator the water vessel 14 of a pressure-regulator is formed, through the water of which project the ends a and b of a pipe 13, one of which leads to the 85 fan and the other to the gas-generator at 15, while a branch pipe 17, furnished with a tap 16, leads also to the gas-generator at 18 and to the gas-delivery pipe 19. The gas-generator communicates also with the pipe 20, 90 which supplies the crude liquid used and can be cut off by a valve 22, actuated by a float 21. The said pressure-regulator consists of an inverted vessel 23, over which reaches a double-armed lever 25, fulcrumed to the regulator at 29. The said inverted vessel is adapted 95 to rise and push against the long arm of the lever 25, while the short arm is connected by a rod 26 to an angular lever 27, which is shaped to form a brake 28, adapted to act 100 upon a pulley 29, secured upon the shaft 10. The crude liquid in the gas-generator is tempered by heating the water in the said jacket by a gas-flame fed from the pipe 19 by means

of the branch pipe 30. The water-jacket 6 also communicates at 32 and 33 with a pipe 31, which has an enlarged part 34, serving as a heating-surface and containing a division-
5 plate, so that the water passes over a com-
paratively large heating-surface. The burner
36 has a by-pass, and the flame is regulated by
the tap 38, furnished with a lever 39, placed
under the influence of a spring 40 and that
10 of the electromagnets 41, which latter oper-
ate the armature 42, connected with the said
tap-lever. Into the circuit 43 of the electro-
magnets a thermometer 44 is inserted, the
15 quicksilver of which when at a certain height
causes the circuit to be closed and at a cer-
tain depth to be opened. The thermometer
is located in a double-walled vessel 45, se-
cured to the jacket 6, and the space between
20 the said walls communicates with the latter,
so that the water in the jacket 6 has access
to the said space, and its temperature con-
trols the state of the thermometer. This de-
vice is so arranged that when the quicksilver
25 column of the thermometer is at a certain
height the electric circuit closes and the gas-
feed will be cut off by the armature actuat-
ing the tap 38, while when the quicksilver
30 column falls the spring 40 will open the tap
38, owing to the electric circuit being broken,
and the flame will be lighted through the by-
pass. The device described may, however,
35 be so modified that when the electric cir-
cuit closes gas will be admitted and cut off
when the circuit breaks. This modification is
principally used for crude liquids difficult to
evaporate.

In starting the apparatus described the crude liquid (gasoline and the like) is admitted into the gas-generator 5 and its level regu-
40 lated by the float 21. The rope-drum is then
set in motion, which causes the fan 1, shaft
10, and disks 11 to rotate, the latter at a higher
speed than the former. The buckets 9 rise
45 and empty the crude liquid over the sides of
the disks 10, faced with porous material and
formed with ports, which latter allow the li-
quid to pass from side to side of the said disks.
The gas is generated, as well known, by evapo-
50 ration, the fan 1 supplying through pipe 13
the necessary air, which passes the inverted
vessel 23 of the pressure-regulator 14. The
inverted vessel 23 rises and falls in accord-
ance with the variation of pressure therein
55 and at a certain excess of pressure pushes
against the lever 25, which causes the brake-
lever 28 to be applied to the pulley 29, and
thereby the supply of air accordingly reduced,
and thus the gasification retarded or inter-
rupted. The branch pipe 17 permits of mix-

ing with the gas issuing at 18 an additional 60
volume of air, if deemed necessary.

What I claim as my invention, and desire
to secure by Letters Patent, is—

1. A gas-producing apparatus, consisting
of a gas-generator divided into compartments 65
which communicate with each other, disks
contained therein secured upon a rotary shaft
and formed with buckets, apertures and faced
with porous material, the said gas-generator
communicating with a fan which supplies the 70
air required and being geared up with the
said disk shaft and the said cups adapted to
raise and empty the liquid hydrocarbon, over
the said rotating disks for evaporation there-
by, all substantially as and for the purpose 75
set forth.

2. In a gas-generator formed with compart-
ments containing rotary disks with ports,
buckets and sides faced with porous material
and communicating with a fan geared up with 80
the shaft of the said disks, in combination, an
inverted vessel capable of rising and falling
in a water vessel containing air-pipes leading
respectively to the said fan and generator, a
double-armed lever fulcrumed above the said 85
inverted vessel and connected to a brake-le-
ver and a brake-pulley on the said disk shaft,
the said inverted vessel being adapted to rise
at a certain excess of pressure therein and
through the said double-armed lever apply 90
the brake-lever to the respective pulley and
thereby retard or interrupt the air-supply
and thus the gasification in the generator, all
substantially as and for the purpose set forth.

3. In a gas-producing apparatus having a 95
gas-generator surrounded by a water-jacket,
in combination, a gas-burner and tap having
a by-pass, the flame of which is adapted to
heat a portion of the water-circulating pipe
100 of the said jacket for the purpose of temper-
ing the water in the latter, a lever on the said
tap under the influence of a spring and an
electromagnet and a thermometer subjected
105 to the action of the tempered water in the
said jacket, and electrically connected with
the said electromagnet, which thermometer
at a certain maximum state closes and at a
certain minimum state opens the circuit of
110 the said electromagnet and thus allows the
said spring to open and the said electromag-
net to close the said tap respectively, all sub-
stantially as and for the purpose set forth.

In witness whereof I have hereunto set my
hand in presence of two witnesses.

MAX GÖHLER.
